EXERCISE TREADMILL

Wayne E. Quinton, 3051 44th Ave. W.,
Seattle, Wash. 98199

Filed Jan. 15, 1968, Ser. No. 10,172

Term of patent 14 years

(Cl. D34—5)

Fig. 1.

Fig. 2.

Fig. 6.

Fig. 5.

Fig. 4.

FIGURE 1 is a perspective view of an exercise treadmill in operating position showing my new design;

FIGURE 2 is a front elevation view thereof;

FIGURE 3 is a side elevation view thereof;

FIGURE 4 is a top plan view thereof;

FIGURE 5 is a rear elevation view thereof; and

FIGURE 6 is a perspective view of the treadmill standing upright in storage position with the handle assemblies in storage position.

I claim:

The ornamental design for an exercise treadmill, as shown.
